USE OF NON-ADHESIVE MATERIALS AS STENCIL COPY, AND THE METHOD OF RETAINING SAME TO THE SCREEN, IN SCREEN PROCESS PRINTING

Jack Q. Larson, Mason City, Iowa

Application December 12, 1956, Serial No. 627,957

1 Claim. (Cl. 101—129)

The present invention relates to screen processing with the use of non-adhesive stencil materials and has for an object, the improvements in the method of separating an imprinted sheet or material from the screen mesh, without the additional use of adhesives, to hold stencil copy to screen.

Heretofore screen processing has been limited with the use of thin materials as stencil copy, because if an adhesive was not used to hold thin materials to screen before screening of coloring material, upon the release of the imprinted copy or material, from screen, some or all of the thin materials may separate from the screen and stay on the imprinted copy or material, thus resulting in loss of copy from screen, loss of time etc.

The principle object of my invention is the improved method of separating flexible imprinted material from the screen mesh, without the losing or removal of stencil copy from screen, by the application of pressure across screen by means of a suitable thin device, such as a stiff card, roller, bar, squeegee or the like, while at the same time grasping the imprinted material and then simultaneously peeling the imprinted material away from stencil copy and screen, while moving the line of application of pressure.

In use with my method, either the card or screen frame may move, during line of application of pressure or one may move separately or independently, while the other is in a stationary position. The card as employed, may consist of various materials, in applying or with the use of applying pressure and may vary in sizes, suitable to accommodate the stencil copy and screen employed.

With the foregoing object and improvement in view, the invention will be more fully described and pointed out in the following descriptions and claim.

Figure 1 is a prepared screen in a position showing the bottom view.

2

Figure 2 is a fragmental cross-sectional side view of a screen as in Figure 1.

Figure 3 is a cross-sectional view of screen as in Figure 2 showing impressing of screen, during pressure method.

Figure 4 is an imprinted copy, showing that intricate as well as large stencil copy is now possible, in screening without adhering stencil copy to screen with adhesives, glues or the like.

10 Referring more particularly to the drawings; after the screen 15 has been raised, following the imprinting of coloring material 14 on an imprinted material 11, by pressure being applied across imprinted material 11, against the screen mesh 12, with the use of a card 10, then 15 grasping the imprinted material 11 in the general area 11a while simultaneously peeling the imprinted material 11 away and moving the line of application of pressure, the various stencil copy 13 is left intact on screen mesh 12.

By pressure applied across imprinted material 11 that 20 has been screened coloring material 14 upon, pressure exists on the stencil copy 13, against screen mesh 12. By grasping the imprinted material 11 in the general area, best shown as 11a in Figs. 1 and 2 and then simultaneously peeling the imprinted material 11 away while moving 25 the line of application of pressure, the adhesive action of the coloring material 14 on the imprinted material 11 is broken from the edges of the stencil copy 13, thereby leaving stencil copy 13 intact to screen mesh 12 by the action of coloring material 14 remaining in mesh.

30 Variations in my invention of the improvements in the method of separating various flexible materials from the screen mesh are assumed and expected within the scope of the enclosed invention by the following claim.

What I claim is:

35 The method of separating flexible imprinted material from a stencil screen having stencil material retained thereon by the coloring material used for printing which comprises applying pressure across the screen near one end thereof, grasping the margin of the imprinted material adjacent the said end of the screen, and then simultaneously peeling the imprinted material away from the screen while moving the line of application of the pressure along the screen to the other end thereof, whereby the 40 stencil material remains intact on the screen and the 45 flexible imprinted material is separated therefrom.
